UNITED STATES PATENT OFFICE.

JAMES PARKINSON, OF TORONTO, ONTARIO, CANADA.

DISPLAY SIGN.

Application filed January 31, 1927. Serial No. 164,918.

My invention relates to improvements in display signs and methods of making same and the object of the invention is to produce in a flat surface a raised or embossed letter effect without raising the surface of the letter from a flush position with the background.

My invention consists of a display sign constructed and arranged all as hereinafter more particularly described and illustrated in the accompanying drawing in which:

Fig. 1 is a front elevational view of a sign cut by my particular method, a piece of glass being positioned upon the face of the sign to keep it from becoming scratched or otherwise disfigured.

Fig. 2 is an enlarged cross sectional view taken through the line 2—2 Figure 1.

Like characters of reference indicate corresponding parts in the different views.

1 is a flat metal sheet preferably formed of aluminum or some bright similar metal in which grooves can be made with comparative ease and 2 is a sheet of glass of similar dimensions to the metal sheet adapted to be positioned upon the outer face thereof when the sign is completed ready for use. The sheet of glass can be held in position by any suitable means such as the U-shaped clips 3.

The particular outline of the sign required is first lightly engraved upon the surface of the sheet of metal which of course is dull due to the rolling process in its manufacture. A suitable graving tool is then used

to deeply incise the outline of the sign into the metal, such incisions which are indicated by reference numerals 4 being in the form of a groove substantially triangular cross section as clearly illustrated in Figure 2.

It has been found through experiment that the best reflectory outline is obtained by forming the incisions or groove of right angle triangular cross section, the hypotenuse of the triangle forming the bottom of

the incision, the right angle corner being positioned at the outer margin of the outline.

When the cutting of the outline incisions has been completed the surface of the sign surrounding the outline is darkened by any suitable means such as enamel so as to form a back ground in effective contrast to the letter outlined in the aforesaid groove 4 the bright metallic surface forming the base of the groove serves to throw the letter surrounded thereby into relief so as to give the effect of an embossed letter which is produced on a surface which is flush throughout.

I have utilized the incisions in combination with such unpolished surface to form an effective contrast which will readily catch the eye. Furthermore by darkening one portion of the sign I have devised a very efficient means for insuring the prominence of the display without increasing the cost of manufacture to any appreciable extent.

It may also be pointed out that when my sign is used at night in a location such as a store window that it gives a very beautiful effect, particularly when all the lights in the window are turned off. The comparatively little light which strikes the sign from the street reflects upon the reflecting surface of the sign making the letters stand out in a very bright illuminated outline, rendering the sign more clearly visible than would be in a sign which is constructed under any method hitherto devised.

What I claim as my invention is:

A display sign comprising a plate formed of bright metal having a dulled surface and grooves having side walls extending perpendicularly to the face of the sign, and a bottom wall extending from the bottom of the side wall to the face of the sign at the opposite side of the groove and formed by cutting into the metal of the plate to outline a letter, character or figure and to expose the bright metal to contrast with the dull surface formed by the letter, character or figure.

JAMES PARKINSON.
